(57) **CLAIM**

The ornamental design for a freestanding stove, as shown
and described.

DESCRIPTION

FIG. 1 is a front isometric view of my new design for a
freestanding stove.

FIG. 2 is a front side elevation view thereof;

FIG. 3 is a right side elevation view thereof, the left side
being a mirror view of FIG. 3.

FIG. 4 is a back side elevation view of FIG. 1.

FIG. 5 is a top plan view thereof;

FIG. 6 is a bottom plan thereof; and,

FIG. 7 is a front plan view of the embodiment of FIG. 1 with
the doors in the open position.

The broken lines depict portions of the freestanding stove
that form no part of the claim.
